HEEL COVER TO PROTECT BOWLING ALLEYS

Harry T. Nichols, Bridgeport, Conn.

Application January 29, 1945, Serial No. 575,011

5 Claims. (Cl. 36—72)

This invention relates to a cover for the heels of shoes, and particularly a cover for heels of shoes of bowlers to protect the alleys, and has for an object to provide a simple and effective construction which may be easily and quickly applied to and removed from the heels of the shoes, and will cover the lower face of the heels so as to protect the surface of the alley from smearing or black marks made by rubbing off of part of the material of composition heels, or injury from nails or such elements.

It is also an object to provide such a device which may be manufactured at low cost so as to be supplied to bowlers at much less expense than special bowling shoes.

Another object is to provide a construction which will not need stitching and riveting and the like in forming the parts or securing them together.

With the foregoing and other objects in view I have devised the construction illustrated in the accompanying drawing forming a part of this specification. It is, however, to be understood the device is not limited to the specific details of construction and arrangement shown, but may embody various changes and modifications within the scope of the invention.

In the drawing:

Fig. 1 is a side elevation of the heel end portion of the shoe showing my improved cover applied thereto;

Fig. 2 is a bottom plan view thereof;

Fig. 3 is a detail perspective view showing how the side ears and the securing band are fastened together without stitching or riveting, and

Fig. 4 is a development showing how the cover may be cut from a strip of leather or similar material to reduce waste to a minimum.

Serious injury is often caused to the surface of bowling alleys by bowlers using ordinary shoes, by nails or other parts of the heels, and with rubber or composition heels the material rubs off onto the surface of the alley smearing it and also causing relatively sticky parts on the surface. Also, heels of regular shoes are apt to slip on the alleys causing the bowler to fall and be injured. It is not practicable to require bowlers to always use special bowling shoes, and besides, such shoes are relatively expensive. To overcome these objections I have devised a simple and effective pad which may be easily and quickly mounted so as to cover the lower surface of the heel and protect the surface of the alley from injury, and they also may be made of material which will not be apt to slip and cause injury to the bowler.

This device comprises a pad 5, which may be of any suitable material, but is preferably of flexible leather as this effectively protects the surface of the alley and is of light weight so as not to add material weight or bulk to the shoe. It also can be made of a surface so as to prevent slipping. I have found a very satisfactory material to be a flexible leather. This pad includes a body portion 6 adapted to cover the lower face of the heel 1, and includes an upwardly extending portion 8 at its forward edge adapted to be positioned and lie in front of the upwardly extending front wall 9 of the heel and cooperate therewith to hold the cover from sliding backward.

At each of the opposite side edges of the body portion 6 and the flange portion 8 are ears 10 and 11 respectively, extending upwardly so as to lie along the opposite sides of the heel and heel end portion 12 of the shoe, and a flexible securing means 13 is connected to these ears and passes over the upper edge of the rear end portion 12 of the shoe, as shown in Fig. 1. The ears 10 and 11 on each side are connected together so as to hold the forward portion 8 of the pad in a generally upright position to lie in front of the forward wall 9 of the heel, and also to form openings 14 at the opposite forward corners of the pad to receive the corners 15 of the heel, which therefore also hold the pad, by engaging the edges of the opening, against slipping backwards. As the flexible securing means 13 holds it against sliding forwardly the pad is effectively secured in position on the heel. The securing means 13 may be of any suitable flexible material, but is preferably an elastic band secured to the ears 10 and 11 and passing over the heel end portion of the shoe, and is of such length that it is stretched when applied to the shoe so as to securely hold the pad in place.

This securing band can also be used for securing the ears 10 and 11 together, thus doing away with stitching or riveting or similar means, which might be apt to separate and permit the ears to come apart, and it also materially reduces the cost of manufacture. For this purpose the ears 10 and 11 are pierced with openings 16 and 17 respectively adjacent their upper or free ends, and then the band 13 is passed inwardly through the openings 17 and 16 with the ears in overlapped relation, over the upper edges of the ears and then downwardly and rearwardly again through the opening 17, as clearly indicated in Fig. 3, with its free end 18 lying between the two ears 10 and 11. By drawing the band tight, the

two ears 10 and 11 are effectively secured together and the end of the band bound and securely held so that there is no danger of its pulling loose from the ears.

In Fig. 4 is shown how the pads 5 may be cut from a strip 19 of leather or other material from which they may be made, such for example as canvas, felt or similar material, if desired. By reversing the blanks and more or less nesting them, as indicated, the waste of material may be reduced to a minimum.

It will be clear from the above that these protective pads or covers are of very simple construction and may be manufactured at low cost, that they may be very easily and quickly applied to the heel by merely placing them on the face of the heel, and when the heel has corners, with these front corners of the heel in the openings 14, and passing the band 13 over the upper portion of the heel end of the shoe. They are as easily removed by merely sliding off the band 13. These covers will effectively cover the lower face of the heel to prevent marring or smearing of the surface of the alley by rubbing off of the material of the heel or by injury from nails or similar articles, and also will provide a surface which will not slip on the surface of the alley sufficiently to cause injury to the bowler.

Having thus set forth the nature of my invention, what I claim is:

1. A heel cover of the character described comprising a pad including a body portion adapted to cover the lower face of a heel and a forward portion adapted to extend upwardly at the front edge of the heel, upwardly extending ears at the side edges of the body and forward portions secured together to form openings to receive the forward corners of the heel to hold the pad from sliding backwards on the heel, and a flexible securing means connected to the ears and adapted to pass over the upper part of the heel end of a shoe to hold the pad on the heel.

2. A heel cover of the character described comprising a pad adapted to cover the lower face of a heel, an upwardly extending flange at the forward end of the pad adapted to lie in front of the forward wall of the heel, upwardly extending ears at the opposite edges of the pad and flange, said ears on each side being connected together and adapted to engage opposite sides of the heel to hold the pad in place, and a flexible securing means connected to the ears and adapted to pass over the upper part of the heel end of the shoe to hold the pad in place on the heel.

3. A heel cover of the character described com-

prising a pad adapted to cover the lower face of a heel, an upwardly extending flange at the forward end of the pad adapted to lie in front of the forward wall of the heel, upwardly extending ears at the opposite edges of the pad and flange each provided with an opening adjacent its free end, a securing means comprising a flexible strip passing through the openings in the overlapped ears on each side, then extending over the free edges of the ears and again through one of the openings so that its free end extends between the ears and the overlapped ears are secured together, and said securing means also adapted to pass around the upper part of the heel end of the shoe to hold the pad in place on the heel with said ears at the opposite sides thereof.

4. A heel cover of the character described comprising a pad adapted to cover the lower face of a heel, an upwardly extending flange at the forward end of the pad adapted to lie in front of the forward wall of the heel, upwardly extending ears at the opposite edges of the pad and flange, said ears on each side being connected together to form openings adapted to receive the forward corners of the heel and cooperate therewith to hold the pad from sliding backward on the heel, said ears on each side also adapted to lie against the side of the heel to hold the pad against lateral movement, and a flexible elastic connected to the ears on each side and adapted to pass around the upper part of the heel end of the shoe to retain the pad in place on the heel.

5. A heel cover of the character described comprising a pad including a body portion adapted to cover the lower face of a heel and a forward portion adapted to extend upwardly at the front edge of the heel, upwardly extending ears at the side edges of the body and forward portions each provided with an opening adjacent its free end, a flexible elastic passing through the openings in the two ears on the opposite side edges of the pad while in overlapped relation and then passing over a free edge of the ears and again through one of the openings so its free end is between the ears to thus secure the ears together and form an opening between them adapted to receive a forward corner of the heel and cooperate therewith to hold the pad from sliding backward on the heel, said elastic being adapted to pass around the upper portion of the heel end of the shoe to retain the pad in place on the heel, and the ears being also adapted to engage the sides of the heel to hold the pad against lateral movement.

HARRY T. NICHOLS.
